COMBINED GUARD RAIL AND CONTROL PANEL FOR A COOK STOVE

Frank Breckenridge, Whittier, and Thomas D. Tweedie,
Monrovia, Calif., assignors to O'Keefe & Merritt Com-
pany, Los Angeles, Calif., a corporation of California

Application April 8, 1958, Serial No. 50,381

Term of patent 14 years

(Cl. D81—25)

Fig. 1 is a front elevation view of a combined guard rail and control panel for a cook stove embodying our new design;

Fig. 2 is a sectional view taken on the line 2—2 on Fig. 1 in the direction of the arrows;

Fig. 3 is an end elevational view of our new design; and,

Fig. 4 is an enlarged fragmentary, detailed view of the pattern illustrated on the lower panel of Fig. 1.

We claim:

The ornamental design for a combined guard rail and control panel for a cook stove, as shown.
